(57) **CLAIM**

The ornamental design for a chest for firewood and associated items, as shown and described.

DESCRIPTION

FIG. 1 is a front perspective view of a chest for firewood and associated items showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken line disclosure in the views is understood to represent portions of the chest which form no part of the claimed design.
